(57) **CLAIM**

The ornamental design for a bike-mounted holder for a cell phone and other electronic devices, as shown and described.

DESCRIPTION

FIG. 1 is a perspective view of a bike-mounted holder for a cell phone and other electronic devices; FIG. 2 is a right end view of the bike-mounted holder for a cell phone and other electronic devices shown in FIG. 1, FIG. 3 is a top view of the bike-mounted holder for a cell phone and other electronic devices shown in FIG. 2, FIG. 4 is a left side view of the bike-mounted holder for a cell phone and other electronic devices shown in FIG. 2, FIG. 5 is right side view of the bike-mounted holder for a cell phone and other electronic devices shown in FIG. 2, FIG. 6 is a bottom view of the bike-mounted holder for a cell phone and other electronic devices shown in FIG. 2; and, FIG. 7 is an end view opposite to that of FIG. 2 of the bike-mounted holder for a cell phone and other electronic devices.

The broken lines adjacent the shaded areas represent boundaries, while the other broken lines represent unclaimed environmental structure; none of the broken lines form part of the claimed design.

The bike-mounted holder for a cell phone and other electronic devices is used for supporting for example a holder for a cell phone or another electronic device on a handle bar of a bike.
